B. F. HAYS.
EASY CHAIR.

Patented Dec. 17, 1834.

Dec. 17, 1834

57

Benjamin F. Hays, of Pittsfield, Mass.

Letters Patent.

The schedule referred to in these Letters Patent, making part of the same, containing a description in the words of the said Benjamin Franklin Hays, himself, of his improvement in an easy chair -

To all to whom these presents shall come; Be it known that I, Benjamin F. Hays, of Pittsfield, in the County of Berkshire, and State of Massachusetts, have invented a new and useful improvement in an easy chair, and that the following is a full and exact description thereof -

Fig. 1. on the drawing, is a side view of said chair - A. frame work of suitable dimensions for size and strength. B. back attached by pivot C, made secure at any given angle by the strap P, cord or other substance fixed to the back at D, and the frame at E, by a buckle or rolling cylinder, around which the strap may be coiled by means of a crank, or some simple safe fastening. F. head piece attached to side pieces of back by the pivot H, to be turned up for a head board as at G, when the back is laid into the position of a bed, represented by the dotted lines BDFG, I. foot pieces attached to frame by pivot K, made in two parts so that either half can be raised to any given angle and made secure by strap cord or other substance attached to foot pieces at M, M, M, and to the frame at L, by a similar method as at E. N. panels drawn out of foot pieces, as represented by the horizontal dotted lines, to give sufficient length for a bed, and by means of sliding into the foot pieces, when in a perpendicular position, the chair can be made of ordinary height. O. foot board attached to the foot pieces by means of a wire, cord, or otherwise, with screws so arranged on each end of foot pieces as to raise or lower the foot board at pleasure, to be used while in a chair, or when in a bed, or dispensed with in either. P.P.P, strap, cord, or other substance to make back & foot pieces fast at any angle. R.R. side rockers confined to the legs of chair by the pivots S, S, T; socket & sliding joint in side rockers, which joint is made secure by a mortise, boxed with hard substance.

Drawings

in the end of each of the rockers R.R. where they meet in the socket T, and slide on the friction rollers V.V. or the same result may be produced by having the sliding motion operate on the pivots S.S. WW, rivets fastening the socket T. to a piece of wood or metal joined to the short arm of the lever W. by a pin, making a joint at X. V. lever attached to an arbor extending cross-wise and fixed to the frame by means of staples or otherwise, to the opposite end of which arbor, on the opposite side of the frame is fixed another short arm of the lever V, to which is attached a pitman or compound arm, socket, and rockers, exactly corresponding with R.R. V.V. T. W.W. X. V. The lever V. being detached from the frame to which it is made fast at Y, by means of a staple V. spiral or common spring, is drawn upward and backward (the rockers R.R. at the same time sliding into the socket T) until the lever pitman & side rockers occupy the position defined by the dotted lines, or the pit man may be raised perpendicularly by coggs meshing into a wheel on the short arm of lever V. leaving the chain resting upon the cross rockers a. which are made fast by the rods b.b. one end of each of which is made fast by a staple to the cross rockers at a.a. the other end of each made fast by a staple to a sliding bar, represented by a dotted line in the frame at C. & attached to the arbor on which it slides by staples or a hole passing thro' the bar horizontally corresponding with the size of the arbor. to which sliding bar is attached the strap q. cord or other substance, sufficiently strong to move the bar back & forth, on the arbor in a horizontal direction - by which motion the cross rockers a.a. are folded into a horizontal position by turning on the pivots S.S. or pressed out to a perpendicular position as at a.a., d.d. rollers (or castors) attached to frame & pivot S.S. forming a check to either pair of rockers, preventing the chair or from overturning and when both pair of rockers are withdrawn from a rising position, forming wheels on which the whole can be moved at pleasure in any direction. e. breast board attached to arm pieces by a hook staple be elevated at pleasure, forming an eating, working writing, or sleeping top. Fig. 2. showing a front or rear view of chair. A. arbor attached to frame by staples or otherwise. B. long arm of lever outside of chair. C. C. short arm of lever attached to arbor A. at X, directly over the pitman Z Z. on

and socket which are attached to the side rockers, the ends of which are represented at D.D. & C.C. joint in the short arm of lever, corresponding with X in fig. 1. J. ends of sliding bar, to which are attached (the rods b.b. in fig. 1). The ends of which sliding bar rest on the frame work (or rounds) keeping it horizontal while moving back & forth on the arbor, by means of the strap & cord, or other substance attached to the bar at J. and passing through strap with friction rollers as at G.G. on either side of the chain. by drawing the strap on the right side, the sliding bar is moved on the arbor A to H. as having the rods b.b. (as in fig. 1). attached to the bar, the cross rockers are fold into a horizontal position (represented by the dotted lines lying in a horizontal direction) turning on the pins S.S. K shows the position or angle of the rods b.b. when the sliding bar is at H. and the cross rockers folded in. L edge view of rollers or castors - an arbor or axle with light wheels may be attached to the frame, so as to enable an invalid who has the use of his arms to move himself in any direction with ease -

The back and sides can be stuffed and trimmed in any style of plain or elegance. All the changes can be performed by an individual himself while sitting in the chair. he can by the lever V raise himself from a roll to a rocking chair. from a rocking chair to a cradle motion by raising the strap q, and letting back the lever V. By letting down the back and raising the foot pieces, one at a time an invalid can make his own bed by raising the back and letting down one of the foot pieces, and changing back from the cross to the side rockers. a person with a fractured limb, enjoy the pleasure of a rocking chair without injury. by raising both back and foot pieces, a crib or cradle is formed of any desirable dimensions. The whole is plain and simple in its construction, fitted for all the uses of the nursery and parlor, adapted to all classes of invalids, easily changed into a great variety of positions to suit dropsical, asthmatic, an rheumatic patients - cheap and of convenient size, light & portable, can be conveyed from one apartment or place to another is well calculated for journeying with weak and feeble persons, affording a comfortable bed when needed by the way. well calculated for a hospital, surgeons, dentists chair, and not less adapted for all the ordinary purposes of

common rocking chair, or a single bed, in a private family, or public office. What I claim as my own invention, and not previously known, in the above described machine, is: 1st. holding the back and foot pieces at any given angle by a simple strap & buckle or rolling cylinder, around which the strap or cord may be wound by a crank. 2nd. The sliding panels in the foot pieces, by means of which the chair can be made of ordinary height and the bed of any required length. 3rd. head piece in the back so calculated as to lengthen the back when in a chair, and shorten it when in a bed, forming a head piece when in a perpendicular position, and head board when in a horizontal position. 4th. The side rockers with a joint in the middle so made as to be operated on, by a lever, by which an individual can raise himself by a simple and easy motion, from a rolling to a rocking chair. 5th. cross rockers confined by the same pivot (though not necessarily) which confines the side rockers. 6th. Sliding or moving bar to which the cross rockers are attached by rods & staples, and by the moving of which bar on the arbor, the cross rockers are folded into a horizontal, or pressed out into a perpendicular position. 7th. Rollers and castors, so applied as to form a check to both pair of rockers, and operating on the same pivot.
